HEEL COVERING MACHINE

William P. Devine, Dorchester, Mass., assignor to
United Shoe Machinery Corporation, Paterson,
N. J., a corporation of New Jersey

Application July 22, 1930, Serial No. 469,752
Renewed July 3, 1933

47 Claims. (Cl. 12—42)

This invention relates to machines for applying sheet material such as celluloid, leather, fabric, or the like, to the outer face of a boot or shoe heel, the invention being illustrated as embodied in a machine for folding the edges of the material over the tread of the heel, the top of the heel and the breast of the heel, as well as to apply it to the outer face of the heel.

The invention is exemplified with reference to an apparatus or machine such as hereinafter set forth in the specification and particularly pointed out in the claims.

The illustrated machine is provided with mechanism including an improved resilient member for quickly and effectively wrapping the sheet material or cover around the outer face of the heel and folding it over the edges of the heel as particularly set forth in the specification and pointed out in the claims.

Referring to the drawings:

Fig. 1 is a front elevation of the illustrated heel covering machine;

Fig. 2 is a sectional elevation of the machine taken on line 2—2, Fig. 1;

Fig. 3 is a plan view, partly in section, of the machine taken on line 3—3, Fig. 2, parts of the machine being broken away to save space in the drawings;

Fig. 4 is a sectional elevation taken on the line 4—4, Fig. 3;

Fig. 5 is a detail sectional elevation taken on line 5—5, Fig. 3;

Fig. 6 is a perspective view of one of the cover gauges;

Fig. 7 is a sectional elevation taken on line 4—4, Fig. 3, illustrating the heel in position for the back portion thereof to contact with the cover blank;

Fig. 8 is a sectional elevation similar to Fig. 7 illustrating the heel forced part way down during the covering operation thereof;

Fig. 9 is a sectional elevation similar to Figs. 7 and 8 illustrating the heel in its lowermost position after the cover has been applied to the outer face and folded over the edges thereof;

Fig. 10 is a plan view of a portion of a band with an elastic pad superimposed thereon and with a heel cover shown in position thereon in dotted lines;

Fig. 11 is a transverse section of the band and pad taken on line 11—11, Fig. 10, a heel supported by the pad being shown in dotted lines;

Fig. 12 is a longitudinal section taken on line 12—12 of Fig. 10;

Fig. 13 is a transverse section of a band with a modified form of elastic pad thereon;

Fig. 14 is a transverse section of a band with another modified form of pad superimposed thereon;

Fig. 15 is a transverse section of a band with still another modified form of elastic pad superimposed thereon;

Fig. 16 is a plan view of a heel cover; and

Fig. 17 is a detail plan view of an alternative form of friction roller.

In the drawings (Figs. 1, 2, and 3) 15 is the frame of the illustrated machine and 16 is a band of flexible material, preferably elastic. The opposite ends of the band are clamped between clamp plates 17 and 18 (Figs. 3 and 4) which are fastened to slides 19 and 20, said slides being slidably mounted on the frame of the machine. The opposite sides of the band are preferably left free. The slides 19 and 20 are oppositely disposed and are spaced apart at 21. Rocker plates 22 and 23 are pivoted by means of studs 24 and 25 to the adjacent ends of the slides 19 and 20 respectively and the adjacent faces 22' and 23' of said rocker plates normally converge toward the rear edge of the band 16 as illustrated in Fig. 4, the pivotal studs 24 and 25 being located approximately between the front and rear ends of the rocker plates 22 and 23 or midway between the sides of the slides 19 and 20 and of the sides of the band 16.

Anti-friction rolls 26 and 27 are rotatably mounted in the upper inner corners of the rocker plates 22 and 23 and the band 16 normally rests upon these rolls. The rolls 26 and 27 normally converge toward the rear edge of the band 16 and are parallel to the inclined inner faces 22' and 23' of the rocker plates 22 and 23.

A pad 28 of resilient or elastic material is positioned upon the band 16. It is fastened thereto preferably in the central portion thereof as at 29, Fig. 11. This form of pad, as illustrated in Fig. 11, consists of two layers of elastic material 30 and 31, these two layers being joined together at 29' in the central portion thereof. In the upper face of the elastic pad 28 there are provided two arcuate grooves *a* and *b* which extend from one end *c* of the elastic pad to the other end *d* thereof. A portion *f* of the pad bounded by the grooves *a* and *b* and the ends *c* and *d* forms approximately the contour of the development of the outer face of a shoe heel, and a transverse section of the pad 10 in Fig. 11, or anywhere between the ends *c* and *d* of the pad is convexly curved on its upper surface. The upper faces of the inner portion *g* and the outer portion *h* of the pad are preferably approximately in the same

plane as the top of the convexed portion *f*. The outer portions or edge portions of the pad *28* are preferably not attached to the band *16*.

In Fig. 10 a cover *40* is shown in dotted lines positioned and in Fig. 11 in full lines in correct position relatively to the pad, to be applied to the outer face of a heel.

The movement of the slides *19* and *20* toward each other is limited by screws *32* and *33* respectively, these screws abutting against the frame when the slides are closest together. The movement of the slides away from each other is limited by studs *34* and *35* which have screw-threaded engagement with the frame of the machine and are held in adjusted position by set screws *36* and *37*. The screws *32* and *33* have screw-threaded engagement with the slides *19* and *20* respectively and are held in adjusted position by lock nuts *38* and *39*.

The cover *40* is of sheet material, celluloid, leather, fabric, or any material with which it is desired to cover the outer face of the heel. The said cover is placed by the operator on the pad *28*, as particularly illustrated in Figs. 3 and 4, and the said cover has a curvilinear top edge *41*, a curvilinear bottom edge *42* and converging end edges *43* and *44*. In order to enable the operator to place the cover *40* in correct position upon the pad *28* gauge fingers *45* and *46* are provided.

These gauge fingers and the gauge blocks *47* and *48* upon which they are supported are duplicates, except that one is right handed and the other left handed, so that a description of one will equally well apply to the other.

Referring to the gauge finger *46*, therefore, and to Figs. 3, 4 and 6. Said gauge finger consists of an angle piece having a vertical flange *49* and a horizontal flange *50* with a stop *51* extending downwardly from an arm *52* which is fast to or integral with the vertical flange *49*. The vertical flange *49* converges toward the rear edge of the band *16*. The horizontal flange *50* extends rearwardly at *53* beneath the gauge block *48* and is pivotally mounted thereon by means of a stud *54* diagrammatically illustrated in Fig. 6 and also illustrated in Figs. 2 and 3. The stud *54* has screw-threaded engagement with the block *48* and is located beneath the same. Between the head of the stud *54* and the portion *53* of the gauge finger a friction washer *55* is interposed, so that by adjusting the stud *54*, more or less friction may be applied to the portion *53* of the gauge finger to regulate the difficulty or ease with which the feed finger *46* may be moved or swiveled upon said stud *54*, thus enabling the said feed finger to be positioned to engage different sizes or shapes of heel covers.

The gauge blocks *47* and *48* are slidably mounted upon a cross bar *56*, Figs. 1, 2 and 3, fast to an arm *58* and said gauge blocks may be adjusted toward or away from each other by a right and left threaded screw *57* mounted upon the arm *58* which is clamped to a standard *59* by a screw *60*. The standard *59*, see Fig. 5, is provided with flanges *61* adjustably mounted in a slot *62* provided in a slide *63* and is fastened or clamped to the slide *63* by means of a screw *64*, so that the standard *59* can be adjusted toward or away from the band *16* and then set in an adjusted position relatively thereto, by means of the screw *64*. When the standard *59* is thus adjusted, the arm *58*, screw *57*, cross bar *56*, gauge blocks *47* and *48* and gauge fingers *45* and *46* will be likewise adjusted relatively to the band *16*.

The slide *63* slides in ways *65* provided in a plate *66* which is fastened by screws *67* to a bracket *68*, the bracket *68* being rigidly fastened to the frame *15* and forming in effect a portion thereof. A spring *69* is fastened at one end thereof to a pin *70*, Fig. 2, which is fastened to the plate *66* and at the other end to a pin *71* fast to the slide *63*, this spring tending normally to hold the slide *63*, with its parts supported thereon, in its forward position. The slide *63*, with the parts mounted thereon, may, however, be automatically moved rearwardly or toward the right, Fig. 2, by a member *72* which has an inclined lower edge *73* adapted to engage the inner face of the rear wall *74* of the slide *63*, the said slide being provided with a slot *75* into which the member *72* projects during a downward movement. The member *72* projects downwardly from a slide *76* slidably mounted in ways *77* on the frame of the machine.

A vertical reciprocatory motion is imparted to the slide *76* by a lever *78* which is pivoted at *79* to the frame of the machine and has a rocking motion imparted thereto by suitable mechanism not shown in the drawings. The forward end of the lever *78* is arcuate shaped at *80* and *81* and these arcuate portions bear against the lower face *82* of an arm *83* which projects rearwardly from the slide *76* and the arcuate edge *81* of said lever bears against a face *84* on an arm *85* extending rearwardly from said slide *76*, so that a rocking movement of the lever *78* imparts a reciprocatory vertical movement to the slide *76*. On the front of the slide *76* is fastened a bracket *86* which has integral therewith a forwardly extending arm *87* and a laterally extending arm *88* and another laterally extending arm *89* on the outer end of the arm *87*. The arm *88* has a presser *90* adjustably attached thereto by a shank *91* bifurcated at its lower end to receive an ear *92* on the presser *90*, said ear being pivotally mounted upon the bifurcated portion of the shank *91* by a pivotal pin *93*. The shank *91* is adjustable vertically in the arm *88* and is clamped thereto by a screw *94*.

The arm *89* has a vertical rod *95* slidably mounted therein and held in frictional engagement therewith by a friction pin *96* and screw *97* with a spring *98* interposed between the screw *97* and the friction pin *96*. A side gauge *99* for the heel has screw-threaded engagement with the lower end of the rod *95*, the said rod being split so that the gauge can be clamped thereto by means of a clamp screw *100* and the said gauge is further locked in position in the lower end of the rod *95* by a nut *101*. A vertical reciprocatory movement is imparted to the rod *95* by the movement of the plunger slide *76* and the bracket *87* forming in effect a portion thereof, and by the arm *89*.

The distance to which the rod *95* can be moved upwardly or downwardly is limited by a pair of collars *102* and *103* which are clamped to the rod *95* by screws *104* and *105* respectively, so that as the slide *76* moves upwardly, the rod *95* and the gauge *99* at the lower end thereof will move with it until the collar *103* engages the underside of an arm *106* fast to the frame of the machine and projecting between the collars *102* and *103*, the rod *95* having sliding movement in the outer end of said arm *106*. The movement of the rod *95* downwardly is limited by the collar *102*. When said collar strikes the arm *106* the downward movement of the rod *95* will stop and the arm *89* on the bracket *86* will slide on the said rod *95*, thus a limited upward movement and a limited downward movement is imparted to the rod *95*.

with its side gauge 99 by the reciprocatory movement of the slide 76.

The bracket 81, forming in function a portion of the slide 76, has flanges 107 projecting downwardly therefrom, and between these flanges the upper end of a plunger member 108 is clamped by a screw 109. The plunger member 108 is extended at its lower end to form a contact member 110 having an inclined inner edge 111 which is adapted to bear against and position a heel 112 when the said heel is placed thereagainst by the operator, the inclined edge 111 bearing against the top of the heel. The breast of the heel is positioned by a contact member 113 which is pivoted at 114 to a stud 115 which is clamped to the plunger member 108 by a clamp screw 116. The contact member 113 is therefore adjustable up and down and it also tips on the pivot 114 to conform to varying angles of the breast and top of the heel with each other, and by adjusting the clamp member 113 up and down different thicknesses of heels from front to back may be accommodated, so that when the plunger arrives at its lowermost point, the rear portion of the outer face of the heel will be at the same level independent of the form or size of the heel. When the heel is positioned by the operator with the top in engagement with the edge 111 of the contact member 110 of the plunger 108 and with its breast in engagement with the contact member 113, the side of the heel bears against a flange 99' on the side of the gauge 99.

Beneath the band 16 and positioned out of alignment with the upper edge of the heel which is to be covered there is provided an edge folder 117 which has a shank 118 extending downwardly therefrom and supported in an adjustable arm 119, the arm 119 being slideable inwardly and outwardly within a bracket 120 which projects upwardly from the base 121 of the machine frame, and the arm 119 is locked in adjusted position by means of a set screw 122. The upper edge 123 of the folder 117 is curved and the rear face of said folder is concaved at 124, the said folder being adjusted in proper position relatively to the heel which is being covered so as to fold the upper edge at the rear of the heel inwardly over the upper rear edge of the heel when the said heel is moved downwardly as hereinafter described. An elastic cushion 125 is mounted upon a support 126 which, in turn, is fastened to the frame of the machine, said elastic cushion being in alignment with the presser 90.

In Fig. 13 an elastic pad 127 is illustrated attached to the band 16 and having recessed portions 128 provided in its underside thereof.

In Fig. 14 another form of elastic pad 129 is illustrated in which the upper layer 130 is provided with recesses 131 in its underside, the same being joined to a lower layer 132 by adhesive in the central portion thereof, the layer 132 being attached to the band 16 by adhesive in the central portion thereof.

In Fig. 15 another modification 133 of an elastic pad is illustrated attached to the band 16 by adhesive, this elastic pad 133 having a convex upper surface taken transversely thereof.

In Fig. 17 another form of anti-friction roller 26' is illustrated which is adapted to be used instead of the rollers 26 and 27, Fig. 4, the same being tapered from the central portion thereof to the ends.

In order that different bands 16 may be used upon the machine and one readily substituted

for another as, for example, if the band becomes worn and needs to be replaced, or if different shaped pads be necessitated by different shaped outer faces of the heels, it is desirable that the band 16 should be easily and quickly removed and another band 16 inserted in its place and for this reason the ends of the band, as hereinbefore stated, are clamped between clamp plates 17 and 18, see Figs. 3 and 4. These clamp plates are fastened together by screws 133 and the clamp plate 17 is provided with a tongue 134 which projects into a groove 135, the said tongue and groove extending transversely of the band 16 and clamp the end of the band therebetween. The clamp plates 17 and 18 thus clamped together and having the band clamped therebetween are readily attached to or detached from the slides 19 and 20 by means of pins 136 and 137 which project through corresponding grooves in the clamp plate 18, so that in attaching the band to the machine, one of the pair of clamp plates is attached to the slide 19 by slipping the clamp plate 18 over the pin 136 and the other of the pair of clamp plates is attached to the slide 20 by slipping the corresponding clamp plate 18 over the pin 137, the band 16 being preferably stretched during this operation. It will be noted that the clamp plates 17 and 18 are thus pivotally attached to the slides 19 and 20, so that the band may, if necessary, adjust itself slightly to varying conditions and stresses to which it may be subjected by reason of the ends of the clamp plates attached thereto being capable of swinging or pivoting upon the pins 136 and 137.

The general operation of the mechanism hereinbefore specifically and to some extent in general described is as follows:—The operator having first applied adhesive to the cover 40 and to the outer face of the heel, places the cover with the adhesive face uppermost on the pad 28, as illustrated in Fig. 11, in alignment with the heel 112, being enabled so to do by the gauge fingers 45 and 46, the ends 43 and 44 of the cover being brought to bear against the vertical flanges 49 on these fingers and the curved lower edge 42 of the cover being positioned against the stops 51 on said gauge fingers. The cover now having been correctly positioned, the heel 112 is placed as illustrated in dotted lines, Fig. 2, with its top resting against the contact member 110 and its breast against the contact member 113, with the side of the heel resting against the flange 99' on the side gauge 99. The operator while holding the heel in this position now rocks the lever 73 preferably by means of a foot treadle and connections not shown in the drawings, to cause the slide 76 to descend until the heel engages the cover 40 as illustrated in Fig. 11, that is, with the upper edge of the heel engaging the cover 40 opposite the groove b in the pad 28 and with the lower edge of the heel engaging the cover 40 opposite the groove a in the pad 28. A further downward movement of the heel causes the cover adjacent the edge 41 to be thrust into the groove b and the cover adjacent the groove 42 to be thrust into the groove a, the portion of the cover between said grooves assuming therefore a concavo-convex form to fit the convex portion of the pad between the grooves a and b and the heel is then in the position illustrated in Fig. 7. The operator lets go of the heel when it arrives at the position illustrated in Fig. 7. At this point the side gauge 99 will come to a stop by reason of the collar 102 engaging the arm 106. Further downward movement of the heel will

carry the same away from the flange 99' of the side gauge 99 to the position illustrated in Fig. 8.

The band 16 will be stretched during this portion of the operation and the edge portions of the pad 28 will be folded upwardly around the outer face of the heel, the said edge portions moving out of contact with the band 16 during this part of the operation as illustrated in Fig. 8.

- 10 When the band 16 is stretching, as aforesaid, the pad and band being forced into the space 21 between the rocker plates 22 and 23 will force said rocker plates and the slides 19 and 20, to which they are pivoted, apart, and as the band 16 is fastened at its opposite ends to said slides, the band will be further stretched by this movement a part of the slides, thus bringing extra tension upon the band and firmly and securely wrapping the pad around the outer face of the heel, together with
- 15 the cover for the heel.

The heel 112 is moved down from the position illustrated in Fig. 8 to that illustrated in Fig. 9, and as shown in said Fig. 9 this further movement results in the outer edge portions of the pad 28 being folded in over the breast, tread and top of the said heel. During this downward movement of the heel, the rocker plates 22 and 23 will rock to assume the proper angles relatively to the heel which is being covered. It being noted that the adjacent faces of said rocker plates converge toward the rear edge of the band 16. During the latter part of the downward movement of the heel hereinbefore described, the band 16 will come into contact with the curved upper edge 123 of the folder 117 and with the concave face 124 of said folder and will be folded, together with the pad 28, over the rear upper edge of the heel, thus folding the cover 40 over said rear upper edge.

- 35 40 When the heel, in the downward movement hereinbefore described, arrives at the position illustrated in Fig. 7 and the cover is thereby clamped to the pad 28, the inclined lower edge 73 of the member 72 engages the rear wall 74 of the slide 63 and moves the same rearwardly, together with the standard 59, the cross bar 56, the gauge blocks 47 and 48 and their respective gauge fingers 45 and 46 so as to move them rearwardly from above the cover prior to the molding or folding operation of the cover hereinbefore described.

The operator now releases the treadle and the lever 78 moves to the position illustrated in Fig. 2, thus raising the slide 76 and the parts mounted thereon to the respective positions illustrated in

- 55 Figs. 1 and 2. During this upward movement, the member 72 will release the slide 63 and the spring 69 will return the gauge fingers 45 and 46 to their original positions as illustrated in Fig. 3 and the side gauge will be moved upwardly from the position illustrated in Fig. 7 to the position illustrated in Figs. 1 and 2. Pressure having been released upon the heel 112 the elasticity of the band 16 and the pad 28 will cause said parts to assume their normal positions illustrated in Figs. 3, 4 and 7, the contracting of the band 16 causing the slides 19 and 20 to move toward each other until the stop screws 32 and 33 engage the frame of the machine as illustrated in Figs. 3 and 4.
- 60 70 The operator now removes the covered heel from the pad and band and preferably places it upon the elastic cushion 125 in a reverse position, so that upon the next downward movement of the slide 76 the presser 90 will engage the tread of the heel and press the top of the heel against the

said elastic cushion, thus securely and completely folding and pressing the inturned edges of the cover against the top of the heel and against the bottom thereof.

It will be noted that since substantially the entire pad 28 is free to move with respect to the members or slides 19 and 20, the pad is progressively compressed toward its lateral edges as the cover is being applied to the heel. The pad 28 may, therefore, be said to flow or to creep toward its lateral edges for tensioning the cover positioned between the heel and the pad progressively from the back of the heel to the breast edges of the heel. Such movement of the pad causes the cover to be slightly tensioned as it is applied to the heel and, therefore, prevents wrinkles being formed in the cover during the heel covering operation.

I claim:

1. A device for applying sheet material to a heel comprising an elastic pad having a pair of arcuate grooves in its upper surface extending longitudinally thereof and forming a portion of a contour approximately that of the development of the outer surface of a shoe heel.

2. A device for applying sheet material to a heel comprising an elastic pad having a pair of arcuate grooves in its upper surface extending longitudinally thereof and forming together with the end edges of said pad a contour approximately that of the development of the outer surface of a shoe heel.

3. A device for applying sheet material to a heel comprising a band of flexible sheet material and a pad of elastic material extending over the central portion only of said band and being permanently affixed thereto at the central portion of said pad, which pad has its oppositely disposed sides free with respect to said band.

4. A device for applying sheet material to a heel comprising a band of flexible sheet material, and a pad of elastic material formed of a plurality of layers affixed to said band at the central portion of said pad and having oppositely disposed sides of said pad free with respect to said band.

5. A device for applying sheet material to a heel comprising a band of flexible sheet material, and a pad of elastic material, said pad being formed of a plurality of layers superimposed on each other and having recesses therebetween, the pad being affixed to said band at the central portion of said pad and having oppositely disposed sides of said pad free with respect to said band.

6. An apparatus for covering heels with sheet material having, in combination, a band of flexible material, means to hold opposite ends of said band, a pad of elastic material permanently affixed to said band at its central portion while leaving its oppositely disposed sides free with respect to said band, and means to push the entire outer rear face of a heel against a piece of sheet material resting against said pad.

7. An apparatus for covering heels with sheet material having, in combination, a band of flexible material, means to hold opposite ends of said band while leaving opposite sides of said band free, and a pad of elastic material affixed to said band.

8. An apparatus for covering heels with sheet material having, in combination, a band of flexible material, means to hold opposite ends of said band, and a pad of elastic material affixed to said band at the central portion of said pad and having oppositely disposed sides of said pad free with respect to said band.

9. An apparatus for applying a cover to the outer surface of a heel having in combination, a plunger, a pair of oppositely disposed slides spaced apart at their adjacent ends, a band of flexible material positioned on said slides and attached thereto, a pad of elastic material affixed to said band, and means to move said plunger toward said band whereby the outer face of a heel positioned between said plunger and a cover positioned on said pad may have said cover applied thereto.
10. An apparatus for applying a cover to the outer surface of a heel having, in combination, a plunger, a pair of oppositely disposed slides spaced apart at their adjacent ends, a band of flexible material positioned on said slides and attached thereto adjacent its opposite ends, a pad of elastic material affixed to said band, and means to move said plunger toward said band whereby the outer face of a heel positioned between said plunger and a cover positioned on said pad, may have said cover applied thereto.
11. An apparatus for applying a cover to the outer surface of a heel having, in combination, a plunger, a pair of oppositely disposed slides spaced apart at their adjacent ends, a band of flexible material positioned on said slides and attached thereto, means to limit the distance to which said slides may be moved toward each other, a pad of elastic material affixed to said band, and means to move said plunger toward said band whereby the outer face of a heel positioned between said plunger and a cover positioned on said pad, may have said cover applied thereto.
12. An apparatus for applying a cover to the outer surface of a heel having, in combination, a plunger, a pair of oppositely disposed slides spaced apart at their adjacent ends, a band of flexible material positioned on said slides and attached thereto, means to limit the distance to which said slides may be moved apart, a pad of elastic material affixed to said band, and means to move said plunger toward said band whereby the outer face of a heel positioned between said plunger and a cover positioned on said pad, may have said cover applied thereto.
13. An apparatus for applying a cover to a heel having, in combination, a band of flexible material, means to hold opposite ends of said material, and a gauge adjacent said band and adjustable relatively thereto, whereby said cover may be positioned on said band.
14. An apparatus for applying a cover to a heel having, in combination, a band of flexible material, means to hold opposite ends of said material, and a gauge embodying a pair of oppositely disposed gauge fingers projecting over and adjacent to said band, whereby said cover may be positioned on said band.
15. An apparatus for applying a cover to a heel having, in combination, a band of flexible material, means to hold opposite ends of said material, a gauge embodying a pair of oppositely disposed gauge fingers projecting over and adjacent to said band and adjustable relatively to each other and to said band.
16. An apparatus for applying a cover to a heel having, in combination, a band of flexible material, means to hold opposite ends of said material, and a gauge embodying a pair of oppositely disposed gauge fingers projecting over and adjacent to said band and converging toward the rear edge of said band, said fingers being adapted to engage opposite ends of a cover positioned on said band.
17. An apparatus for applying a cover to a heel having, in combination, a band of flexible material, means to hold opposite ends of said material, a gauge embodying a pair of oppositely disposed gauge fingers projecting over and adjacent to said band, whereby said cover may be positioned on said band, and means to move said fingers out of alignment with said band.
18. An apparatus for applying a cover to a heel having, in combination, a band of flexible material, means to hold opposite ends of said material, and a gauge embodying a pair of oppositely disposed pivotally mounted gauge fingers projecting over and adjacent to said band, whereby said cover may be positioned on said band.
19. An apparatus for applying a cover to the outer surface of a heel having, in combination, a plunger, a pair of oppositely disposed slides spaced apart at their adjacent ends, a roll pivotally mounted on each of the adjacent ends of said slides respectively, a band of flexible material positioned on said slides and attached thereto, a pad of elastic material affixed to said band, and means to move said plunger toward said band, whereby the outer face of a heel positioned between said plunger and a cover positioned on said pad may have said cover applied thereto.
20. An apparatus for applying a cover to the outer surface of a heel having, in combination, a plunger, a band of flexible material in alignment with said plunger, means to hold opposite ends of said band, a pad of elastic material affixed to said band, and means to move said plunger toward said band, whereby the outer face of the heel positioned between said plunger and a cover positioned on said pad may have said cover applied thereto.
21. An apparatus for applying a cover to the outer surface of a heel having, in combination, a band of flexible material, means to hold opposite ends of said band, a plunger in alignment with said band, means to move said plunger toward said band, a contact member on the bottom of said plunger adapted to engage the top of a heel, and a contact member pivotally mounted on the bottom of said plunger adapted to engage the breast of said heel.
22. An apparatus for applying a cover to the outer surface of a heel having, in combination, a band of flexible material, means to hold opposite ends of said band, a plunger in alignment with said band, means to move said plunger toward said band, a contact member on the bottom of said plunger adapted to engage the top of a heel, and a contact member pivotally mounted on the bottom of said plunger adapted to engage the breast of said heel and adjustable toward and away from said band.
23. An apparatus for applying a cover to the outer surface of a heel having, in combination, a band of flexible material, means to hold opposite ends of said band, a plunger in alignment with said band, means to move said plunger toward said band, a contact member on the bottom of said plunger adapted to engage the top of a heel, a contact member on the bottom of said plunger adapted to engage the breast of said heel, and a gauge adapted to engage the side of a heel when the same is positioned in contact with said contact members.
24. An apparatus for applying a cover to the outer surface of a heel having, in combination,

a band of flexible material, means to hold opposite ends of said band, a plunger in alignment with said band, means to move said plunger toward said band, a contact member on the bottom 5 of said plunger adapted to engage the top of a heel, a contact member on the bottom of said plunger adapted to engage the breast of said heel, and a gauge adapted to engage the side of a heel positioned to engage said contact members, said gauge being slidably mounted on the 10 frame of said machine and adapted to be moved toward and away from said band by said plunger.

25. An apparatus for applying a cover to the outer surface of a heel having, in combination, a band of flexible material, means to hold opposite ends of said band, a plunger in alignment with said band, means to move said plunger toward said band, a contact member on the bottom 15 of said plunger adapted to engage the top of a heel, a contact member on the bottom of said plunger adapted to engage the breast of said heel, a gauge adapted to engage the side of a heel positioned to engage said contact members, a rod to which said gauge is fastened, said rod 20 being slidably mounted on said plunger, frictional means between said rod and said plunger, an arm mounted on said frame, and means on said rod adapted to engage said arm, whereby movement imparted to said rod and to said gauge may 25 be limited.

30. An apparatus for applying a cover to the outer surface of a heel having, in combination, a slide, a plunger on said slide, means to impart a vertical movement to said slide, a band of 35 flexible material in alignment with said plunger, means to hold opposite ends of said band, a pad of elastic material affixed to said band, whereby the outer face of a heel positioned between said plunger and a cover positioned on said pad may 40 have said cover applied thereto, a presser fast to said plunger slide, and an elastic cushion in alignment with said presser, whereby a heel interposed between said cushion and said presser may be subjected to pressure.

45. An apparatus for applying a cover to the outer surface of a heel having, in combination, a slide, a plunger on said slide, means to impart a vertical movement to said slide, a band of flexible material in alignment with said plunger, means to hold opposite ends of said band, a pad of elastic material affixed to said band, whereby the outer face of the heel positioned between said plunger and a cover positioned on said pad may 50 have said cover applied thereto, a presser pivotally mounted on said plunger slide, and an elastic cushion in alignment with said presser, whereby a heel interposed between said cushion and said presser may be subjected to pressure.

55. An apparatus for applying a cover to the outer surface of a heel having, in combination, a plunger, a band of flexible material in alignment with said plunger, means to hold opposite ends of said band, a pad of elastic material affixed to said band, means to move said plunger toward 60 said band, whereby the outer face of a heel positioned between said plunger and a cover positioned on said pad may have said cover applied thereto, and a folder positioned beneath said band out of alignment with the upper edge of said heel, 65 whereby the edge of said cover may be folded over said upper edge.

70. An apparatus for applying a cover to the outer face of a heel having, in combination, a plunger, a pair of oppositely disposed slides spaced 75 apart at their adjacent ends, a roll tapered to-

ward its ends and pivotally mounted upon each of the adjacent ends of said slides respectively, a band of flexible material positioned on said slides and attached thereto, a pad of elastic material affixed to said band, and means to move said plunger toward said band, whereby the outer face of a heel positioned between said plunger and a cover positioned on said pad may have said cover applied thereto.

75. An apparatus for covering heels with sheet material having, in combination, a plunger, an elastic band, an elastic pad on said band in alignment with said plunger, a pair of members spaced apart on which said elastic band rests and to which its opposite ends are fastened while leaving it free at its opposite sides, and means to cause relative movement between said plunger with the breast of a heel contacting therewith and said band, whereby a piece of sheet material positioned upon said pad in predetermined position relatively to said heel and interposed between the band and heel may be applied to said heel and thrust into the space between said members and folded around the outer face of said heel.

80. An apparatus for applying a cover to the outer surface of a heel having, in combination, a pair of oppositely disposed slides spaced apart at their adjacent ends, a band of flexible material, a pair of clamp plates fast to each of the opposite ends of said band, and means to detachably connect said clamp plates to said slides.

85. An apparatus for applying a cover to the outer surface of a heel having, in combination, a pair of oppositely disposed slides spaced apart at their adjacent ends, a band of flexible material, a pair of clamp plates fast to each of the opposite ends of said band, and means to pivotally attach said clamp plates to said slides.

90. An apparatus for applying a cover to the outer surface of a heel having, in combination, a pair of oppositely disposed slides spaced apart at their adjacent ends, a band of flexible material, a pair of clamp plates fast to each of the opposite ends of said band, and a pin on each of said slides projecting through a hole in one of said clamp plates at each of the opposite ends of said band respectively, whereby said clamp plates are pivotally mounted upon said slides.

95. A heel covering machine having, in combination, a support for a heel, a pad of resilient material, means comprising a pair of members constructed and arranged to support the pad and to permit free movement of substantially the entire pad with respect to said members, and mechanism for causing relative movement of the support and said means to apply a cover positioned between the heel and the pad to the back of the heel and then around the sides and upon the lateral portions of the breast face of the heel, said support and said means being constructed and arranged to compress the pad progressively along opposite sides of the heel and to cause the pad to flow toward its lateral edges thereby to tension the cover as the same is applied to the heel.

100. A heel covering machine having, in combination, a support for a heel, a relatively thick pad of soft elastic material for receiving a cover to be applied to the heel, means for moving the support to press the heel against the cover supported by the pad, and means including members constructed and arranged to support the pad against the pressure of the heel and to cooperate with the support in applying the cover first along the back of the heel and then progressively around the sides of the heel.

opposite sides of the heel, said pad being constructed and arranged to be displaced toward its lateral portions as it is applied to the heel thereby to insure the proper tensioning of the 5 cover as it is applied to the heel.

36. A heel covering machine having, in combination, a carrier for a heel, a rubber pad of substantial thickness, a deformable backing for the pad, said pad having its lateral portions free with 10 respect to said backing, and means for moving the carrier and the backing to cause the pad to apply a cover positioned between the heel and the pad first to the rear end of the heel and then progressively to opposite sides of the heel and 15 finally upon the lateral portions of the breast face of the heel.

37. In a heel covering machine, a support for a heel, a resilient pad provided with a convex surface for receiving a cover which is to be applied to the heel, means including members for supporting the pad, mechanism for moving the support and the members relatively to each other to cause a cover supported by the pad to be wrapped around the heel, substantially the entire pad being free to flow toward its margins upon movement of the support and the members thereby progressively to tension the cover from the back of the heel to the breast of the same and to inturn the lateral margins of the cover upon 30 the breast of the heel as the pad is wrapped around the heel.

38. A heel covering machine having, in combination, a support constructed and arranged to receive a heel, a resilient pad of substantial thickness, means comprising a pair of members which are arranged to support the pad and are spaced to provide a gap, substantially the entire pad being constructed and mounted for creeping movement with respect to said means, and mechanism 35 for moving the support relatively to said means to wrap a portion of a cover positioned upon the pad about the heel, said means also comprising a yielding brace for the portion of the pad which bridges said gap and said members being mounted for movement for cooperating with the support to distort the pad and thereby to wrap other portions of the cover about the heel.

39. A heel covering machine having, in combination, a holder for a heel, a pair of members spaced from each other to provide a recess, a pad of resilient material arranged to bridge the recess, a resilient support for the portion of the pad which bridges the recess, and mechanism for moving the holder to force the heel against a portion of the cover upon the part of the pad which bridges said recess and is backed by said resilient support to apply the cover to the back of the heel, said members being mounted for movement to cooperate with the holder in applying the cover to the sides of the heel.

40. A heel covering machine having, in combination, a support for a heel, a pair of movable members spaced to form a gap, a pad of resilient material for supporting a heel cover, mechanism for moving the support to cause the pad to enter the gap thereby to wrap the pad around the heel for applying the cover to the same, and means for yieldingly bracing the portion of the pad which bridges said gap during the cover applying operation, said pad being free to creep toward its lateral margins during the movement of the support and the members thereby progressively to tension the cover as it is applied to the heel.

75 41. A heel covering machine having, in com-

bination, a holder for a heel, a pair of members spaced from each other to provide a recess, a pad of resilient material arranged to bridge the recess, a resilient support for the portion of the pad which bridges said recess, and mechanism 5 for moving the holder to force the heel against the portion of the cover located upon the part of the pad which bridges said recess and is backed by said resilient support to apply the cover to the back of the heel, said members being mounted for movement to cooperate with the holder in applying the cover to the sides of the heel, substantially the entire pad being free to move relatively to the resilient support and the members in order to permit the pad to creep toward its lateral edges 10 during the cover-applying operation thereby to stretch the cover as it is applied to the heel in order to avoid forming wrinkles in the cover.

42. A heel covering machine having, in combination, a support for a heel, a pad of resilient 20 material, members for supporting the pad, means for effecting relative movement of the support and the members to cause the pad to apply a cover positioned upon the same to the heel, and a gauge arranged adjacent to the pad for positioning the cover relatively to the heel and to the pad, said gauge being mounted for movement to prevent interference of the same with the pad and the heel while the cover is being applied to the heel.

43. A heel covering machine having, in combination, a pad of readily compressible material for receiving a cover to be applied to a heel, a gauge projecting over and arranged adjacent to the pad for positioning the cover with respect 35 to the pad, a support for the heel, means for effecting relative movement of the support and the pad to apply the cover to the heel, and mechanism for moving the gauge away from the pad to permit the cover to be applied to the heel. 40

44. In a heel covering machine, a resilient pad one side of which is provided with a pair of arcuate depressions connected by a convex surface, a support for a heel, and means for causing relative movement of the support and the pad to 45 wrap a cover positioned between the heel and the pad around the heel.

45. A machine for operating upon shoes having, in combination, a support for one shoe part, a relatively thick pad of elastic material for 50 receiving another shoe part, means for effecting relative movement of the support and the pad to apply portions of one shoe part to the other, and a backing constructed and arranged to brace the pad during said relative movement 55 and to cooperate with said support for causing the pad to creep progressively from a portion of initial contact of the shoe parts relatively to the first-named shoe part thereby to tension the second-named shoe part as it is applied to the 60 first-named shoe part.

46. A machine for operating upon shoes having, in combination, a resilient pad of substantial thickness for receiving a flexible shoe part, spaced members, a holder for a rigid shoe part, 65 means for moving the holder in a predetermined path relatively to the pad, and a backing of resilient material positioned between said members and constructed and arranged yieldingly to support the pad against the pressure of the 70 rigid shoe part carried by the holder, said backing being constructed and arranged to cooperate with the holder for causing portions of the flexible shoe part to be progressively wrapped under tension around the rigid shoe part, the 75

members being mounted for movement in paths disposed substantially at right angles to the path of movement of the holder to cooperate with the holder for forcing the pad around other portions 5 of the rigid shoe part thereby to cause other portions of the flexible shoe part to be progressively wrapped under tension around said rigid shoe part.

47. A heel-covering machine having, in combination, a support constructed and arranged to receive a heel, a pair of members spaced from each other to form a gap, a pad of resilient material constructed and arranged to bridge said gap and to support a cover in predetermined re-

lation to the support, said pad having its sides free with respect to the members, mechanism for moving the support relatively to the pad to force the heel against the cover upon the pad and into the gap thereby to apply portions of the cover to the heel, and means for yieldingly bracing the portion of the pad which bridges said gap during the above cover-applying operation, said members being mounted for movement relatively to the heel support and constructed and arranged to cooperate with the same in applying other portions of the cover to the heel. 5 10

WILLIAM P. DEVINE.
